(57) CLAIM

The ornamental design for a foot shaped bottle, as shown and described.

DESCRIPTION

FIG. 1 is a front view of the foot shaped bottle, according to the present application;

FIG. 2 is a left view thereof;

FIG. 3 is a right view thereof;

FIG. 4 is a top view thereof;

FIG. 5 is a bottom view thereof; and,

FIG. 6 is an enlarged perspective right view thereof, according to the present application.

The broken line showing is for illustrative purposes only, and forms no part of the claimed design.
